UNITED STATES PATENT OFFICE.

WILLIAM CULLEN MORRIS, OF FLUSHING, AND GEORGE E. WOODS, OF ASTORIA,
NEW YORK.

METHOD AND APPARATUS FOR STORING OIL.

Application filed July 19, 1924. Serial No. 726,922.

To all whom it may concern:

Be it known that we, WILLIAM CULLEN MORRIS and GEORGE E. Woods, citizens of the United States, residing, respectively, 5 in Flushing, Long Island, State of New York, and in Astoria, borough of Queens, city and State of New York, have invented a certain Improvement in Methods and Apparatus for Storing Oil, of which the following is a specification.

The safe storage and delivery of inflammable liquids and more particularly of oil presents a serious problem, because of the great danger of its catching fire, and often 15 of explosion.

Governmental regulations are everywhere prescribed with the end in view of minimizing this danger; but destructive conflagrations, due to lighting or other causes occur 20 from time to time in spite of these regulations. The ideal solution of the problem has not hitherto been proposed.

Our present invention relates to a method and means for conveniently storing and delivering oil or other fluids under conditions of the greatest possible safety inasmuch as our method involves entirely surrounding the inflammable fluid with water.

These ends are accomplished by very simple and easily operated apparatus, and under conditions permitting the oil to be drawn off when needed with the greatest possible ease.

Our invention is illustrated in a preferred form in the accompanying drawing which is a diagrammatic view in vertical section of our apparatus erected within a building of which one wall is shown.

Our improved method of storage and delivery consists in confining the oil or the like within a body of water and in such a manner that this water exerts a static pressure on the oil. When it is desired to draw off more or less of the oil the opening of a 45 valve permits the water pressure to become effective to cause or assist the flow outward of the oil and the filling of the space previously occupied by the oil with water.

To carry out this method we prefer the apparatus exemplified in the drawing, wherein an exterior tank 10 is provided within which is located a smaller inner oil-holding tank 11. The inner tank is preferably provided with a dome 12, up into 50 which extends the open extremity of an oil-

admission pipe 13, provided with a valve 14, which may, if desired, be placed outside of the wall 15 of any building within which our apparatus is placed.

A vent pipe 16 extends upward from the 60 top of the inner tank to the outside of the exterior tank, and this pipe is provided with a valve 17.

The pipe 18 and valve 19 are provided for admitting water to the outer tank 10; and the pipe 20 is supplied to permit movement of air in and out of the tank 10 as the level of the water rises and falls within it.

Flow of water from the outer to the inner tank is permitted by communication near 70 the bottom of the inner tank; for instance by means of simple openings 21 around the lower wall of the tank 11.

Operation of the apparatus is very simple. The oil valve 14 being closed and the 75 vent valve 17 being open, water is admitted through the pipe 18 until it fills the tank 10 and stands at some such level as that shown by the dotted line 22—23, so that the water practically covers the tank 11. The outer 80 tank should be made large enough so that its cubic capacity above the line 22—23 may be at least equal to the entire capacity of the tank 11. This is to accommodate the displacement of water in the tank 10 incident 85 to filling the tank 11 with oil.

The valve 19 being now closed the valve 14 is opened and oil is forced inward through the pipe 13, thus entering at the top of the tank 11. The valve 17 is left open for a 90 few moments to purge any vapor that may be in the dome 12 or just above it, and this valve is then closed. As the oil continues to enter through the pipe 13, it drives the water out of the tank 11 through the openings 95 21, and the water level rises correspondingly in the outer tank.

This continues until the tank 11 is full of oil, when the valve 14 may be closed.

It will thus be seen that the oil is entirely 100 surrounded by water which effectively prevents all access of fire, and at the same time the volume of this water above the line 22—23 is always available for replacing the oil when it is removed.

When using the pipe 13 to draw off the oil, it is only necessary to open the valve 14, when the water level 22—23 will fall, the water entering the tank 11 at the bottom and forcing out the oil through the pipe 13.

Various changes may be made in this apparatus without departing from the scope of the invention, which is not limited to the details herein shown and described.

5. What we claim is:

1. A storing and delivering apparatus for oil and the like, comprising an exterior tank closed at top, bottom and sides, a second tank secured on the bottom of the exterior tank and within the same, the top of the inner tank being closed and its sides perforated adjacent the bottom, the top of the inner tank having a small central dome, a vent pipe leading to the atmosphere from said dome and passing through the top of

the exterior tank, a second vent pipe in the top of the exterior tank, means for admitting water to the outer tank, and a single oil conduit entering substantially at the center of the bottom, terminating in said dome and adapted to selectively fill or drain the inner tank. 20

2. An apparatus as described in claim 1 in which the capacity of the outer tank is at least double that of the inner tank.

In testimony whereof we have hereto set our hands and seals this 9th day of July, 1924.

WILLIAM CULLEN MORRIS.
GEORGE E. WOODS.
